TUNING DEVICE FOR RADIO SETS

Earl C. Booth, Columbus, Ind., assignor to No-
blitt-Sparks Industries, Inc., Columbus, Ind., a
corporation of Indiana

Application August 15, 1935, Serial No. 36,299

2 Claims. (Cl. 116—124.4)

My invention relates to the tuning of a radio receiving set and particularly to that type of set designated as "all wave". In such sets, it is customary to employ the same tuning unit, usually 5 variable condensers, for tuning the set within the limits of each frequency band and to employ switch mechanism for changing the band of frequencies over which the set may be tuned by the tuning unit. The device employed for indicating 10 the setting of the set usually comprises a dial which is angularly adjustable with the movable elements of the tuning condensers and which bears one scale for each band of frequencies 15 which the set is adapted to receive.

It is the object of my invention to produce a tuning and indicating device for an "all wave" 20 radio receiver which will have advantages over devices previously in use. More specifically, it is my object to produce a device in which the exceedingly fine adjustments necessary for the satisfactory 25 reception of extremely high frequencies may be easily made and accurately indicated. A further object of my invention is to produce an adjusting and indicating device which may be simply and economically constructed and which 30 will have a wide application.

In carrying out my invention, I mount on the 35 adjusting shaft of the tuning condensers a dial carrying a plurality of scales co-extensive in circumferential extent and radially displaced from each other. In rear of this dial I place a lamp; and between the lamp and dial I mount a stationary mask having a narrow radial slot through 40 which light may pass to define an index on the surface of the translucent dial. Between this stationary mask and the dial I provide an angularly adjustable sector which has one opening for each scale on the dial, such openings being radially spaced in accordance with the radial 45 spacing of the scales on the dial and also being angularly staggered so that they can successively be brought into alignment with the slot in the stationary mask. The sector is operatively connected to the band selector switch of the radio- 50 receiving set so that the setting of the sector will be coordinated with that of the switch to illuminate only that dial-scale which is used for adjusting the set in the band to which it is made responsive by the band-selector switch.

I prefer to secure adjustments of the condenser 55 shaft through the medium of a speed-reducing device the driven element of which is operatively connected to the condenser shaft through reducing gearing. Preferably, the driven element of the speed-reducing device is provided with a

graduated dial and is arranged to be directly accessible for manual manipulation in order that coarse adjustment of the condensers may be quickly made.

The accompanying drawing illustrates my invention: Fig. 1 is a fragmental vertical section on the line 1—1 of Fig. 2 showing the dials and masks in front elevation with portions broken away to illustrate the construction more clearly; and Fig. 2 is a vertical section on the line 2—2 of Fig. 1.

In the arrangement illustrated in the drawing, the tuning condensers 10 are supported in any desired fashion from the frame 11 of the chassis. The movable elements of the tuning condensers 15 are fixed to a shaft 12 which extends forwardly and terminates adjacent the rear face of the front walls 13 of the cabinet within which the set is enclosed.

Fixed to the shaft 12 near its front end I provide 20 a disk 15 of transparent material the outer edge of which overlaps and is secured to a ring 16 of translucent material carrying a plurality of graduated scales, here shown as three in number.

The scales on the dial 16 are illuminated from 25 the rear by a lamp 17 supported from the frame 11; and between the dial and lamp I mount a stationary mask 18 of translucent material provided with a vertically extending narrow slot 19 having a length sufficient to embrace all the scales 30 of the dial 16.

Loosely mounted on the shaft 12 I provide a swingable sector 21 of translucent material having radially spaced and angularly staggered openings 22, 23, and 24, one for each scale on the dial 35 16, the radial disposition of these openings being such that one of them overlies each of the scales. A link 25 connected to the sector 21 at an eccentric point extends to the outer end of an arm 26 secured to the shaft 27 of the band-selector 40 switch, whereby the setting of the sector 21 will be coordinated with the setting of the band-selector switch. The front wall 13 of the cabinet is provided with an opening in which an escutcheon plate 28 is mounted, such plate having a 45 window through which the illuminated portion of the dial 16 is visible.

The shaft 12 is conveniently adjusted through a speed reducing drive here shown as consisting of a gear 30 secured to the shaft 12 and meshing 50 with a pinion 31 carried by a stub-shaft 32 which is directly connected with a rotatable sleeve 33 carrying an adjusting knob 34. The speed reduction provided by the gearing 30—31 will ordinarily permit sufficiently accurate adjustment of 55

the condensers 10 for reception in the broadcast band; but the fineness of the adjustment thus provided is not adequate to permit satisfactory tuning in the higher-frequency bands. I therefore prefer to provide a speed-reducing drive for the pinion 31.

The speed-reducing drive illustrated in the drawing comprises a pair of stamped sheet-metal disks 35 and 36 formed to provide hubs which receive the sleeve 33 and also to provide an outer race for balls 37 mounted in angularly spaced openings in the sleeve 33. Within the sleeve 33 and rotatable relatively thereto is disposed a shaft 38 which is grooved to provide an inner race for the balls 37. The disks 35 and 36 are held against rotation and are yieldingly forced together, as by a spring 39, to provide for the application of pressure to the balls 37. When the sleeve 33 is adjusted by rotation of the knob 34 the pinion 31 is driven at the same speed, but if the shaft 38 is rotated, as by means of a knob 40 on its outer end, the sleeve 33, and with it the pinion 31, will be driven at a reduced speed.

To give a more accurate indication of the tuning adjustment than is provided by the scales on the dial 16, I may employ an auxiliary graduated dial 45 rotatable with the pinion 31 and conveniently secured to the sleeve 33 ahead of the dial 16 where its graduations are visible through a second window 46 in the escutcheon plate 28. An index for the graduations on the dial 45 may be provided by a slit 47 in a translucent mask 48, the slit 47 passing light from a lamp 49 suitably supported from the frame 11 of the chassis. Conveniently, the mask 48 is supported from the shaft 27 and sleeve 33, the mask being provided, at its lower end, with a hole closely fitting the shaft 27 and, at an intermediate point, with a vertically elongated slot which receives the sleeve 33. The purpose of elongating vertically the opening which receives the sleeve 33 is to accommodate for different spacings of the shaft 27 and sleeve 33.

Conveniently, the mask 48 and the lamps 17 and 49 are supported from a sheet-metal bracket 55, the two lamps 17 and 49 being located respectively above and below such bracket so that light from the lamp 17 will be prevented from striking the dial 45 and light from the lamp 49 will be prevented from striking the dial 16.

In the arrangement illustrated in the drawing, light emitted by the lamp 49 and falling on the dial 45 must pass through the swinging sector 21; and to prevent the interruption of too much light by this sector, it is provided with an arcuate slot 56 having a sufficient angular extent to prevent interference with light from the lamp 49 throughout the entire range of sector movement. Light from the lamp 49 illuminating the dial 45

must also pass through the disk 15 which supports the dial 16; but as that disk is of clear material, it does not interfere with the satisfactory illumination of the dial 45.

In the arrangement illustrated in the drawing, the axis of the sleeve 33 lies within the periphery of the dial 16 and, in fact, within the periphery of the disk 15. The disk 15, therefore, is provided with an arcuate slot 60 through which the sleeve 33 extends and which has sufficient angular extent not to interfere with movement of the dial 16 throughout its entire range of adjustment.

In the operation of the tuning device described above, the band-selector switch is adjusted under the control of the shaft 27 to adapt the set for the reception of the desired band of signals. This setting of the selector switch automatically places the sector 21 in position so that the proper scale on the dial 16 will be illuminated by light passing through one of the openings 22, 23, or 24. The tuning condensers 10 are then roughly adjusted by rotation of the knob 34; and if a finer adjustment is necessary, it may be secured by manipulation of the knob 40. Because of the speed-reducing connection provided by the gears 30 and 31 between the condenser shaft 12 and the sleeve 33, a very accurate indication of the condenser-setting may be obtained by reading both the dial 16 and the dial 45.

I claim as my invention:

1. Control means for a radio receiving set having a tuning device provided with a rotatably adjustable tuning element, a graduated dial mounted on said tuning element for rotation therewith, a speed-reducing mechanism having rotatable driving and driven members, reduction gearing operatively interconnecting said driven member with said tuning element, a second graduated dial rotatable with said driven element, and a control knob rotatable with each of said driving and driven elements and accessible for manual manipulation.

2. Control means for a radio receiving set having a tuning device provided with a rotatably adjustable tuning element, a graduated dial mounted on said tuning element for rotation therewith, a rotatable member, said dial being provided with an arcuate slot through which said rotatable member extends, speed-reducing gearing operatively interconnecting said rotatable member and tuning element, a second graduated dial mounted on and rotatable with said rotatable member, said first named dial having a transparent central portion overlapped by said second dial, and a light-source in rear of both dials and positioned to cast light through the transparent central portion of said first dial on to said second dial.

EARL C. BOOTH.
